DEWEY M. KENNEDY AND BENJAMIN H. KENNEDY, OF ROCHESTER, NEW YORK.

INFANT'S BATHTUB.

Application filed July 23, 1923. Serial No. 653,135.

Our present invention relates to bathing appliances and more particularly to bath tubs of the nature used in bathing infants and it has for its object to provide a simple, convenient and preferably collapsible tub of this nature fitted with a folding dressing table having operative and inoperative positions with reference to the tub whereby it may be used, after the bath, to support the infant 10 while it is being dried or dressed. A further object of the invention is to fit the device with a convenient means for protecting the infant from draft while on the dressing table which means may also serve as a rack for accommodating 15 accessories to the bath. To these and other ends the invention resides in certain improvements and combinations of parts all as will be hereinafter more fully described, the novel features being pointed out in the claims 20 at the end of the specification.

In the drawings:

Figure 1 is a side view of the bath tub in operative position with the dressing table in inoperative position the same being constructed 25 in accordance with and illustrating one embodiment of our invention;

Figure 2 is a top view thereof with the parts in the same positions.

Figure 3 is a side view with the dressing 30 table in the first position assumed when it is brought into use;

Figure 4 is a similar view showing the dressing table completely moved to its operative position;

Figure 5 is a side view of the entire device 35 folded to its most compact form;

Figure 6 is a side view similar to Figure 1 but showing the first part of the movement of the dressing table in swinging to operative 40 position and also showing the shield in place;

Figure 7 is a top view of the device as it appears in Figure 6;

Figure 8 is a perspective view of the shield detached and

Figure 9 is a rear view of the device as it appears in Figure 6.

Figure 10 is a view of one of the corners of the device showing the stop shoulders.

Similar reference numerals throughout the 50 several views indicate the same parts.

To first give a general idea of the nature and mode of operation of our bath tub, it preferably embodies a collapsible tub of rub-

ber cloth or similar material mounted on crossed folding legs in the manner of a camp 55 stool. Associated therewith is a dressing table preferably consisting of a frame covered with a fabric stretched thereon which frame has a longitudinal bodily movement combined with a pivotal movement that enables it to assume either an overlying operative position with reference to the tub or a vertical folded position at one side of the tub. A preferably detachable frame carried by the tub support supports a screen partially surrounding both the tub and dressing table in their operative positions to shield the occupant from drafts. This screen is also utilized to furnish racks or pockets for the reception 60 of articles used in connection with the bath. 70

Referring more particularly to the drawings, 1 indicates two pairs of crossed legs of a folding tub support, each pair being pivoted together at 2 and the upper ends of opposite members of the two pairs being connected by side rails 3 and 4. Stretched between these rails is the tub 5, the ends or sides of which are tacked or otherwise secured thereto so that the tub is stretched or extended when the legs are spread in accordance with the weight 75 imposed and is collapsed when the legs are folded in the manner shown in Figure 5.

The dressing table, in the present embodiment of the invention comprises a frame 6 covered with stretched canvas or similar material 7 as shown in Figure 10. It has an operative position in which it overlies the tub as shown in Figure 3, being of the proper size to bridge the end rails 3 and 4 and rest upon the upper ends of the legs 1. It is further 80 connected to the tub supporting legs by links 8 preferably composed of rods each having one of its ends bent at right angles and driven into the inside of the frame 6 as at 9 while the other end is provided with an eye 10 turning on a screw or other pivot 11 on the adjacent leg 1. In putting the tub into use with the dressing table in the position of Figure 3, the latter is moved bodily in an endwise direction on the links 8 to the dotted line position 85 of Figure 6 and is then tilted pivotally on the links at 9 to the vertical full line position of Figure 6 after which it is dropped down to the vertical inoperative position at one side of the tub as shown in Figure 1. The dressing 90 table also occupies this position when the en-

tire device is folded as in Figure 5 so that it lies compactly against the folded legs of the collapsed tub. To bring the dressing table into use from the folded position of Figure 1, these movements are of course reverse and may be accomplished by the user with the use of only one hand by grasping the handle provided at 12 and drawing the dressing table up and over while the infant is held in the other arm.

The position of the tub and its supports in Figure 3 is one in which the legs 1 are spread to the maximum by the weight in the tub and the latter is held taut by the spreading of the legs. This is the lowest position at which the dressing table may be used and is one suitable for a person sitting at the side of the tub. There is also provision for another relatively elevated position of the dressing table suitable for its use while the user is standing. This is shown in Figure 4. Secured in the four corners of the dressing table frame 6 are blocks 13 formed with suitable stop shoulders 14 which the upper ends of the legs 1 are adapted to abut. By drawing the upper ends of the legs together and engaging them with the shoulders the dressing table is elevated as shown while the tub 5 is partially collapsed. The dressing table is preferably habitually used in this position as it takes the strain off of the tub inasmuch as the spreading tendency of the legs is resisted instead by the rigid frame.

The draft screen previously referred to preferably embodies a rectangular wire frame 15 covered with cretonne or similar suitable material 16 carrying racks or pockets 17. The ends of the wire 15 are turned horizontally at 18 to detachably occupy suitable sockets bored in the upper ends of two of the legs 1 as shown in Figures 8 and 9. The shield 16 is thereby disposed along one side of the tub which it occupies in such an offset position that it does not interfere with either the tub or the dressing table or the movements of the latter. An extension 19 of the shield 16 attached to the frame 15 thereof at one end extends forwardly at an adjoining side and is carried at its forward end by a post 20 detachably mounted in a suitable socket in one of the rails 3-4 or in the end of one of the supporting legs. A horizontal web 21 attached to the lower edges of the screen portions 16 and 19 covers the rear edge of the tub beneath the dressing table as shown in Figure 7. The screen is removed of course when the device as a whole is to be collapsed but when in place not only shields the infant but the pockets 17 furnish convenient racks for the reception of the toilet prerequisites.

We claim as our invention:

1. The combination with a support and a bath tub carried thereby, of an overlying flexible dressing table and links pivotally con-

nected to the support and the dressing table respectively, adapting the latter to be swung both endwise and flatwise to an upright folded position at one side of the tub.

2. The combination with supporting legs and a bath tub carried thereby, of an overlying flexible dressing table embodying a frame having a fabric stretched thereon and links pivotally connected to the outer sides of the legs and to the inner sides of the dressing table frame respectively, adapting the dressing table to be swung both endwise and flatwise to an upright folded position at one side of the tub.

3. The combination with a support embodying crossed folding legs pivoted together and a collapsible bath tub carried thereby, of an overlying dressing table and links pivotally connected to the legs and to the dressing table respectively, adapting the latter to swing both endwise and flatwise to a folded position flat against the legs when the latter are folded.

4. The combination with a folding support and a collapsible bath tub carried thereby, of a screen disposed to project above the bath tub when the latter is extended and detachably connected to the support.

5. The combination with a folding support, a collapsible bath tub carried thereby and an overlying dressing table adapted to be swung both edgewise and flatwise to an upright folded position at one side of the tub, of a screen carried by the support disposed to project above the bath tub when the latter is extended and above the dressing table when the latter is in operative position, and racks disposed upon the face of the screen for the reception of bathing appliances.

6. The combination with a folding support and a collapsible bath tub carried thereby, of an overlying dressing table adapted to be swung both endwise and flatwise to an upright folded position at one side of the tub and a screen disposed to project above the latter when it is extended and detachably connected to the folding support, said screen being arranged in an offset position at one side of the tub and clear of the path of movement of the dressing table.

7. The combination with a support embodying crossed folding legs pivoted together and a collapsible bath tub carried by the upper ends of said legs to normally take the strain of the spreading movement thereof, of a dressing table adapted to overlie the tub in said normal position and also adapted to interlock with the legs in a relatively elevated position to take the strain of their spreading movement when the tub is partially collapsed.

8. The combination with a support embodying crossed folding legs pivoted together and a collapsible bath tub carried by the upper ends of said legs to normally take

the strain of the spreading movement thereof, of a dressing table adapted to overlie the tub in said normal position and also adapted to interlock with the legs in a relatively elevated position to take the strain of their spreading movement when the tub is partially collapsed, and links pivotally con-

nected to the support and to the dressing table, respectively, adapting the latter to be swung both endwise and flatwise to an upright folded position at one side of the tub. 10
